METHOD OF FORMING METAL PORTIONS
OF COIN COLLECTOR HOUSINGS

Allan R. MacLagan, Western Springs, and Fred F. Schuster, Berwyn, Ill., assignors to Western Electric Company, Incorporated, New York, N. Y., a corporation of New York

Application April 14, 1937, Serial No. 136,760

6 Claims. (Cl. 29—148.2)

This invention relates to a method of forming metal articles, and more particularly to a method of producing the front portion of the lower housing for telephone coin collectors.

Telephone pay stations at which coins are deposited by the user in payment for completed calls are provided with receptacles for receiving the deposited coins. In some cases stations of this type are located in public places where there is no attendant. The door of the coin receptacle is exposed and unscrupulous persons sometimes break into the receptacle by prying off the door or cutting away, or otherwise removing a dish shaped front portion of the lower housing, which supports the door to the coin receptacle.

In the usual type of telephone coin collector as disclosed in the O. F. Forsberg U. S. Patent 1,043,219, issued November 5, 1912, the coin receptacle occupies most of the lower housing of the collector except for the coin return opening on one side thereof. It has been customary as shown in the F. A. Hoyt Patent 2,025,390, issued December 24, 1935, not to use hinges for the coin receptacle door, but to form integral with the door a lug extending substantially across the bottom end of the door and forming with the main edge of the door an elongated slot adapted to fit over the lower edge of the coin receptacle opening, which is formed in the front portion of the lower housing. This lug is reinforced by a plurality of vertical ribs integral with the door and extending between the lug. The top of the door is usually held in position by the bolt of a lock which engages a lock lug secured adjacent the upper edge of the coin receptacle opening. The door with its integral lug and ribs comprises a single piece of drop forged steel suitably heat treated to give it a high degree of hardness and toughness. It is, therefore, desirable that the dish shaped front portion of the lower housing which supports the door be also as strong as possible and so formed with respect to the door and its lug and ribs which fits the opening in the housing that it will be very difficult to cut it away or otherwise remove it in attempting to gain access to the coin receptacle.

It has been the practice to form the dish shaped lower front housing portion from mild pressed steel formed to a desired configuration with the outer and inner surfaces of the side walls of the housing disposed at right angles to the face supporting the door and its outer surface in the plane of the sides of a rear portion of the lower housing, but such steel is not so capable of resisting attack as the drop forged door itself. It

has also been proposed to make the lower front housing portion of drop forged steel, but with the various associated assemblies carried within the housing being so compactly arranged, a substitution of a drop forged front for a pressed steel front necessitates that the drop forged front have substantially the same dimensions and configuration as the pressed steel front. Heretofore design and manufacturing difficulties were encountered in producing a drop forged front portion of the lower housing for telephone coin collectors due to the necessity of removing the inner and outer draft, which in standard drop forging practice is normally added metal over that required for the part itself, but is added to provide angular sides to prevent the part sticking in the dies. In producing a lower front housing portion, wherein the principal dimensions are all established by the prior design of standard mechanism housed therein, by drop forging it has been or would have been necessary to remove by multifidous and costly cutting operations this inner and outer excess metal. Another difficulty encountered was in forming clearances in the bottom wall of the proposed drop forged front for the vertical ribs on the door.

An object of the present invention is the provision of an efficient and practical method of producing metal articles, and more particularly to the working of such drop forged dish shaped front portions of the lower housings of telephone coin collectors whereby the difficulties above mentioned are overcome.

In accordance with the above object, the invention as applied to forming the lower front housing portion of a telephone coin collector contemplates a method which comprises forming by drop forging a dish shaped blank with a desired inner and outer configuration except that the top, bottom and side walls are inclined outwardly so that the blank may be withdrawn from the dies. The blank with the parting line at the rear edge is then forced through a reforming punch and die mechanism to remove the inclination of the walls and thereby establish a final predetermined inner and outer configuration, the step terminating in the front wall being formed or swaged to insure its flatness. Subsequently the clearances for the vertical door ribs are formed in the inner surface of the bottom wall by a swaging operation, the front wall is perforated to provide the door and coin return openings, the outer top, bottom and side walls at their rear edges are milled to form a continuous shouldered surface to receive the rear housing portion which is spot welded to the

front portion in flush and abutting relation. A further step comprises milling a door seat around the door openings.

Other objects and advantages of this invention will more fully appear from the accompanying detailed description taken in connection with the accompanying drawings, wherein

Fig. 1 is a plan view of a drop forged dish shaped blank for the lower front housing portion of a telephone coin collector;

Fig. 2 is a fragmentary front elevation of the blank illustrated in Fig. 1;

Fig. 3 is a diagrammatic fragmentary view, partly in section, of a reforming punch and die mechanism illustrating the step of removing the outward inclination of the four sides of the drop forged blank:

Fig. 4 is a front elevation of the blank upon completion of the step illustrated in Fig. 3, and after successive forming and perforating operations to provide clearances in the bottom wall for the door ribs and in the front wall thereof for the door and coin return openings;

Fig. 5 is a horizontal section taken on the line 5—5 of Fig. 4;

Fig. 6 is a vertical section taken on the line 6—6 of Fig. 4 showing the blank at the completion of a further step of milling a door seat around the opening for the door;

Fig. 7 is a front elevation of Fig. 6 showing the housing upon completion of further steps of milling the outer, top, bottom, and side walls and a continuous shoulder adjacent their rear edges to receive the rear housing portion which is spot welded thereto in flush and abutting relation;

Fig. 8 is a vertical section taken on the line 8—8 of Fig. 7 showing diagrammatically the step of simultaneously milling the top and bottom side walls and the forming of the shoulders at their rear edges on the housing to receive the rear housing portion, the opposite side walls being milled in a similar manner;

Fig. 9 is a side view of a telephone coin collector having a drop forged lower front housing portion produced in accordance with the method of this invention spot welded to the rear lower housing portion, and

Fig. 10 is an enlarged fragmentary horizontal section taken on the line 10—10 of Fig. 9.

Referring now to the drawings and particularly to Fig. 9, there is illustrated a telephone coin collector which includes a mounting or base plate 14 and a rear portion of a lower housing 15, a drop forged lower front housing portion produced in accordance with the method of this invention and spot welded to the rear portion of the lower housing being indicated at 16. An upper housing portion 17 which carries well known mechanism completes the housing for the telephone coin collector.

In producing the housing portion 16 a slab of steel of requisite dimensions is formed into a dish shaped blank 19 having front, top, bottom and opposite side walls 20, 21, 22, 23 and 24, respectively, (Figs. 1 and 2) by drop forging in a well known manner. The blank 19 upon completion of the drop forging operation will have a desired inner and outer configuration, except that the top, bottom, and opposite side walls are inclined outwardly in order that the blank may be readily stripped from the forging ram after the forging operations.

The blank 19, upon completion of the forging operations, referring particularly to Figs. 1, 2, 4 and 6, includes a notch 27 formed in the rear

edge of the top wall 21 for freely receiving a part of an assembly depending from the upper housing portion 17, the notch having a depression 28 providing a clearance space for a part carried in the lower rear housing portion 15. Formed on the inner surface of the front wall 20 is a vertical reinforcing rib and foundation 29 for a partition member subsequently welded thereto. Also formed on the inner surface of the front wall 20 is a projecting two part lock bolt strike 30, the lower edges of which, as shown in Fig. 4, are in line with the upper peripheral wall of the door opening. No further reference to the above described formations 27, 28 and 29 on the blank 19 will be made except in describing hereinafter an operation on the lock strike 30.

After the blank 19 has been formed, as shown in Figs. 1 and 2, it is placed in a reforming punch and die mechanism (Fig. 3), the blank resting in a forming aperture 33 of a die 34 for operation 20 upon by a reciprocating shouldered punch 35. The die aperture 33 and punch 35 have a desired configuration and are otherwise suitably shaped to operate upon the walls 21, 22, 23 and 24 to remove the outward inclination thereof without deleterious injury to other portions of the blank. The die 34 normally rests by gravity upon a bed 36 and has a limited vertical movement thereon during the operation of the mechanism. A plurality of screws 37, two of which are illustrated, are threaded at their lower ends into the bed 36, the headed upper ends of the screws having a sliding fit in shouldered apertures in the die 34. The upward movement of the die 34 is limited by the space between the lower surfaces of the screw 37 heads and surfaces 40 of the shouldered apertures. Reciprocally carried in opposite recesses in the upper surface of the bed 36 are spring pressed stripping plungers 41 having inclined faces at their inner ends which normally are pressed outwardly by an auxiliary manually slideable bed plate 42 carried in a continuous channel 43 in the bed 36, the inclined end faces of the plungers engaging opposite sides of the plate. Opposite sides of the plunger recesses are provided with slideways in which ride dovetails formed on the plungers 41 effective to prevent the plungers from moving upwardly, the slideways and dovetails being indicated by the broken lines 44. Pins 47 fixed in the bed 36 and extending into slots in the plungers 41 are effective to limit the inward movement of the plungers during the operation of the mechanism.

In reforming the drop forged blank 19 the punch 35 descends, engages the inner surface of the front wall 20 of the blank, and at the end of its stroke has forced the blank partly through the die aperture 33, and against the upper surface of the auxiliary bed plate 42 to the position indicated in broken outline by the numeral 48. In passing along the die aperture 33, the inclined walls 21, 22, 23 and 24 of the blank 19 will be drawn inwardly and formed at right angles to the front wall 20 and at the same time there will be a slight unavoidable bowing outwardly of the front wall 20 which is flattened or swaged at the termination of the described stroke of the punch 35, when the blank is in the position indicated at 48, by the front wall 20 striking the bed plate 42. It will be noted that when the blank 19 is in this latter position the lower part thereof has passed through the die aperture 33 and is within and spaced at opposite sides from the opposite walls of the continuous channel 43 of the bed 36, the other opposite side walls of the blank below 75

the die also being spaced and free from any confining walls. This spacing of the lower peripheral surface of the blank 19 from any walls of the mechanism permits a free necessary slight flow of metal toward the periphery of the blank at the end of the stroke of the punch 35 when the slight bow in the front wall 20 is flattened.

At the termination of the reforming operation upon the blank 19 indicated by the dotted outline position 48 thereof, the ram 35 is elevated a slight distance and due to the frictional locking grip between the peripheral surface of the reduced shouldered lower end of the ram and the inner surface of the blank and that between the outer surface of the blank and the inner surface of the die aperture 33 the blank and the die 34 are likewise elevated, the die sliding on the screws 37. The described unitary movement of the ram, the blank, and the die is for the purpose of removing the pressure of the blank upon the slidable bed plate 42 and such movement need only be a very slight distance and, therefore, no strain is put on the screws 37.

With the blank 19 thus elevated, the bed plate 42 is slid in the channel 43 of the bed 36 from under the blank by means of a handle 49. The movement of the bed plate 42 permits the spring pressed stripping plungers 41 to move inwardly and their inclined inner end faces engage opposite walls of the blank. Thereafter the ram 35 carrying the blank 19 and the die 34 is caused to descend again, the die being returned to its normal position in engagement with the upper surface of the bed 36 and in the continuing movement of the ram the blank is carried through the die aperture 33 and downwardly until the upper edges of the walls of the blank are sufficiently below the lower surfaces of the stripping plungers 41 to permit the latter to move thereover. In this position of the ram 35 the large upper end thereof has freely entered into the die aperture 33 and is located below the plane of the lower surfaces of the stripping plungers. To permit the stripping plungers 41 to move to the described position over the upper edge of the blank the ram is notched in line with the plungers as indicated in dotted outline at 50.

The ram 35 is now caused to ascend to its normal upper position during which movement the reformed blank 19 is stripped from the ram by the plungers 41 being engaged with the upper edge of the blank and it falls to the bottom of the continuous channel 43 of the bed 36 to the position indicated in dotted outline by the numeral 51. The blank may then be slid out of the channel 43 by moving the bed plate 42 back to its normal position. During the latter movement of the bed plate, cam faces, shown in dotted outline at 54, on the advancing forward end of the plate engage the inner ends of the stripping plungers and move them inwardly to their normal positions. The bed plate 42 is of such length that when it is in its normal position the cam faces 54 thereof will be located beyond the path of the blank 19 while it is being forced through the die by the ram 35 and during the flattening of the front wall 20 of the blank by striking it against the upper surface of the bed plate. The side walls 21, 22, 23 and 24 of the blank 19 upon being removed from the reforming punch and die mechanism will be formed at right angles to the front wall 20, as shown in Figs. 4 and 5.

Following the above described steps of the method three depressions 57 (Figs. 4 and 6) serving as clearances for the vertical door ribs are

formed in the inner surface of the bottom wall 22 of the blank 19. The depressions 57 are simultaneously formed by suitable cooperating swaging dies arranged at opposite sides of the wall of the blank which during operation thereon permit the excess metal displaced or extruded in forming the depressions to flow outwardly to form embossments 58 on the outer surface of the wall 22 which are subsequently removed. Thus the depressions 57 are formed without any deleterious distortion of the wall of the blank.

In a subsequent step of the method the front wall 20 is perforated at 59 and 60 (Figs. 4 and 6) in a single operation to provide openings for the door and coin return openings.

In a succeeding step of the method the projecting two part lock bolt strike 30 is bumped or swaged upon upper surfaces 61 thereof, as viewed in Fig. 5, such surfaces being disposed at right angles to and terminating at their lower edges, as shown in Fig. 4, with the upper peripheral wall of the door opening 59. The purpose of swaging the lock strike surfaces 61 is to flatten them, thereby removing any unevenness thereof resulting from the forging operations or distortion occurring during the perforating of the front wall in forming the door opening.

A further subsequent step of the method consists in bumping or swaging slight depressions or clearances 62, indicated in dotted outline, in the inner surface of the front wall 20 at opposite ends of the coin return opening 60 (Fig. 7) for receiving flanges of an escutcheon plate (not shown) which in the final assembly of the coin collector surrounds the opening.

In successive subsequent steps of the method the outer surfaces of the four side walls are subjected to milling operations to trim them of unevenness, including the removal of the embossments 58 on the bottom wall 22 resulting from the swaging of the three depressions 57 for receiving the door ribs and simultaneously therewith to form shouldered surfaces 65 to subsequently receive the rear housing portion 15 in flush and abutting relation (Figs. 9 and 10). As shown in fragmentary dotted outline at 66 in Fig. 8 a pair of tandem connected milling cutters having a plurality of cutting faces 67 are arranged to simultaneously mill the top and bottom side walls 21 and 22, respectively, and form the shouldered surfaces 65 in one operation across the blank 19. In another operation the side walls 23 and 24 are similarly milled. Following the above described milling operations the blank 19 in another step is caused to rotate past a milling cutter to remove the metal remaining at the four corners of the blank, indicated at 68 (Fig. 7), at the termination of which operation a continuous peripheral shoulder is formed on the blank.

The next step of the method comprises forming, preferably by a milling operation, a continuous depressed door seat 69 (Figs. 6, 7 and 8) in the front wall 20 of the blank 19 around the door opening 59. This is the final step in the method of producing the drop forged dish shaped front portion 16 of the lower housing of telephone coin collectors described above with the exception of minor operations, such as surface grinding and finishing operations.

It is believed that the method of this invention will be fully understood from the above description, and it will be seen that it produces important advantages in the art of working drop forged dish shaped blanks to remove the normal

inner and outer outward flare of the side of the blank, and particularly to an efficient and practical method of working such blanks to produce front portions of the lower housings for telephone coin collectors.

5 While the method of this invention has been disclosed and described in connection with drop forged dish shaped front portions of the lower housings for telephone coin collectors, it will be 10 understood that the invention is capable of application to other types of drop forged dish shaped articles and is only limited by the scope of the appended claims.

15 What is claimed is:

15 1. The method of producing the lower front housing portion of telephone coin collectors comprising forming by drop forging a dish shaped blank having front, top, bottom and side walls with a normal outward flare of the top, bottom 20 and side walls, forcing the blank partially through a die to form said latter walls at predetermined angles to the front wall, swaging the front wall to flatten it at the termination of the top, bottom and side wall forming movement, 25 forming depressions in the inner surface of the bottom wall to provide clearances for door ribs, and cutting openings in the front wall for the door and coin return.

2. The method of producing the lower front 30 housing portion of telephone coin collectors comprising forming by drop forging a dish shaped blank having front, top, bottom and side walls with a normal outward flare of the top, bottom and side walls, forcing the blank partially 35 through a die to form said latter walls at right angles to the front wall, swaging the front wall to flatten it at the termination of the top, bottom and side wall forming movement, forming depressions in the inner surface of the bottom wall to provide clearances for door ribs, cutting 40 openings in the front wall for the door and coin return, and shaping the top, bottom and side walls at their rear edges to form a continuous shouldered surface to receive a rear housing portion.

45 3. The method of producing the lower front housing portion of telephone coin collectors comprising forming by drop forging a dish shaped blank having front, top, bottom and side walls with a normal outward flare of the top, bottom 50 and side walls, forcing the blank partially through a die to form said latter walls at right angles to the front wall, swaging the front wall to flatten it at the termination of the top, bot-

tom and side wall forming movement, swaging depressions in the inner surface of the bottom wall to provide clearances for door ribs, perforating the front wall to provide openings for the door and coin return, and milling the top, bottom and side walls at their rear edges to form a continuous shouldered surface to receive a rear housing portion in flush abutting relation.

5 4. The method of producing the front housing portion of coin collectors comprising forming by drop forging a dish shaped blank having a normal outward flare of the side of the blank, forcing the blank partially through an open die with the edge of the side thereof trailing to form the side at a predetermined angle to the face thereof, 15 then swaging the face to flatten it at the termination of the side forming movement, the face and the adjacent portion of the side being freely spaced from the die during the swaging of the face to permit the metal to flow toward the periphery of the blank, and subsequently forcing the blank completely through the die.

20 5. The method of producing the lower front housing portion of telephone coin collectors comprising forming by drop forging a dish shaped blank having front, top, bottom and side walls 25 with a normal outward inclination of the top, bottom and side walls forcing the blank partially through a die with the edges of the walls trailing to form said latter walls at predetermined angles to the front wall, swaging said front wall against a movable die bed plate to flatten it at the termination of the wall forming movement, the front wall and the adjacent portions 30 of the walls being freely spaced from the die during the swaging of the front wall to permit the metal to flow toward the periphery of the blank, relatively moving the blank and the movable die bed plate to relieve the pressure therebetween, moving the die bed plate out of the path of the 35 blank, and subsequently forcing the blank completely through the die.

40 6. The method of producing the front housing portion of coin collectors comprising drop forging a multi-sided blank having outwardly 45 flaring sides, forcing the blank partially through an open die to form the side walls at predetermined angles to the face of the dish shaped article, swaging the face to insure its flatness, and subsequently forcing the blank completely through 50 the die.
